UNITED STATES PATENT OFFICE.

GEORGE G. FLOYD, OF GRANITE, ILLINOIS, ASSIGNOR TO AMERICAN STEEL FOUNDRIES, OF NEW YORK, N. Y., A CORPORATION OF NEW JERSEY.

CAR-TRUCK SIDE FRAME.

No. 839,572.

Specification of Letters Patent.

Patented Dec. 25, 1906.

Application filed September 24, 1906. Serial No. 335,925.

To all whom it may concern:

Be it known that I, GEORGE G. FLOYD, a citizen of the United States, residing at Granite, in the county of Madison and State of Illinois, have invented certain new and useful Improvements in Car-Truck Side Frames, of which the following is a specification.

My invention relates to car-trucks; and its object is the provision of means in connection with the truck side frames which will readily permit removal of the truck-bolster. To accomplish this object, I use side frames each of which has a recess extending downwardly from the top surface to provide a pocket for the end of the bolster and the bolster-springs. Over this recess and attached to the side frame is a detachable bridge or cap, which forms a guide for the bolster to prevent substantial longitudinal movement thereof. The recess and the top and bottom edges of the side frames are preferably provided with marginal flanges, that at the bottom of the recess being sufficiently widened to form a seat for the springs. These flanges afford convenient means for the attachment of transverse beams or transoms, and desirably I use angle-transoms whose two legs or flanges are riveted, respectively, to the top flange of the side frame and to the side flange of the recess or pocket. A neat construction is to employ the same rivets which fasten the transoms to the frame to hold the bridge over the recess in place.

In the accompanying drawings I have illustrated the preferred embodiments of my invention, like reference characters referring to the same parts throughout.

Figure 1 is a side view of one form of my improved side frame. Fig. 2 is a top plan view of the structure shown in Fig. 1. Fig. 3 is a section on line 3 3 of Fig. 1, the springs being omitted and their positions indicated by dotted lines. Fig. 4 is an enlarged central longitudinal section of the bolster and the side frame. Fig. 5 is a plan view of a part of a side frame showing a modified form of bridge or cap fitted over the recess, and Fig. 6 is a section on a reduced scale on line 6 6 of Fig. 5.

The side frame illustrated in Figs. 1, 2, 3, and 4 comprises a vertical bellied plate or web 10, having a central recess 11 extending downwardly from its upper surface to receive the end of bolster 12 and bolster-springs 13,

and also having the ordinary triangular apertures 14 for the reduction of weight. Extending along the top margin of plate 10 down the side of recess 11 and across its bottom and projecting in opposite directions from the plate or web 10 is a marginal flange 15, which is broadened at the bottom of the recess 11 to form a seat 16 for the springs. Plate or web 10 is also provided along its bottom edge with a marginal flange 17, projecting from both sides thereof. At its end the frame has enlargements or bosses 18, apertured to accommodate the column-bolts, and between seat 16 and flange 17 are other enlargements 19 with holes therethrough to accommodate the bolts or pins 20, which maintain the pedestal tie-bar 21 in position. If desired, the top surface of seat 16 may have bosses or projections 22, adapted to fit within the lower ends of the springs upon which the bolster rests.

Preferably the vertical side flanges of recess 11 and the top flange 15 are at right angles, whereby the pair of angle-transoms 23 may be placed in position with one flange or leg resting upon the top surface of flange 15, while the other leg or flange rests against the inner surface of the recess's side flange. In order to tie or join together the top portions of the side frame on opposite sides of the recess and at the same time form a guide or guides for the end of the bolster, I use on each side frame a bridge 24, bowed upwardly somewhat. Bridge 24 has flat terminal plate portions 25, adapted to rest on the horizontal flanges of transoms 23, and rivets 26 secure together these plate portions, the flanges of the transoms, and flange 15 of the side frame. In order to strengthen this bridge, I provide it with a longitudinal upstanding rib 27, and depending from the bridge into the recess and against the two vertical flanges of transoms 23 are guiding-legs 28, which are secured to the side flanges of the recess by one or more rivets 29, which also pass through the depending legs of the transoms.

The bolster near each end has spaced guiding projections 30, which engage the opposite edges of legs 28, the two parts co-operating to guide the vertical movement of the bolster and at the same time prevent any substantial longitudinal movement thereof.

In order to remove the bolster from the

side frame, it is merely necessary to take out the springs, thereby permitting the bolster to descend sufficiently so that its projections 30 are wholly beneath the guiding-legs 28, and when in such position the bolster can be removed laterally of the side frame, so as to separate the two parts. If desired, however, the bolster may be removed from the side frame by detaching bridge or cap 27, 10 first cutting the rivets and lifting the cap away from the side frame and bolster. The guiding parts thus being separated the bolster can be removed transversely of the side frame.

15 In Figs. 5 and 6 I have shown a modification of the bridge, which has its central portion 31 bowed outwardly, as shown in Fig. 5, and equipped at its outer margin with a depending flange 32. The bolster fits within 20 this cap and is prevented from having substantial longitudinal movement by the flanges 32 of the two caps on opposite sides of the truck, the flanges being of sufficient depth to maintain the bolster in position even 25 though the springs beneath it are considerably compressed. In this type of truck it is necessary to have the guides 30 on the sides of the bolster.

To remove the bolster from a truck having 30 side frames and caps, as shown in Figs. 5 and 6, it is necessary to detach the cap, when the bolster can be readily drawn out without difficulty.

In both forms of side frame the bridge and 35 frame are made of cast metal for the sake of strength and economy of manufacture, but my invention is not necessarily limited to cast-metal side frames.

To those skilled in the art various modifications of the structures shown and described 40 will be apparent, and it should be understood that such modifications fall within the scope of my invention, which is not limited to the details of construction set forth. Several 45 minor modifications may be made in a side frame of this character without departure from the substance of my invention.

I claim—

1. The combination of a car-truck side 50 frame having a recess in its top surface adapted to accommodate the end of a bolster, a bridge-piece extending over said recess and fastened to said side frame, and a bolster, said bolster and bridge coöperating and forming the sole means for that side of the truck to prevent substantial longitudinal movement of said bolster relative to said side frame, substantially as described.

2. The combination of a car-truck side 55 frame having a recess in its top surface adapted to accommodate the end of a bolster, a bridge-piece extending over said recess and

fastened to said side frame, and a bolster having one or more guides coöperating with said bridge-piece to prevent substantial longitudinal movement of said bolster relative to said side frame, said guide or guides and bridge-piece constituting the sole means for that side of the truck to prevent lengthwise shifting of said bolster, substantially as described. 65 70

3. The combination of a car-truck side frame having a recess in its top surface adapted to accommodate the end of a bolster, a bridge-piece extending over said recess and 75 detachably fastened to said side frame, and a bolster having lateral guides coöperating with said bridge-piece to prevent substantial longitudinal movement of said bolster relative to said side frame, said guide or guides 80 and bridge-piece constituting the sole means for that side of the truck to prevent lengthwise shifting of said bolster, substantially as described.

4. The combination of a car-truck side 85 frame having a recess in its top surface adapted to accommodate the end of a bolster, a bridge-piece extending over said recess and detachably fastened to said side frame, said bridge-piece having a portion extending into 90 said recess, a bolster having one or more lugs or ribs adapted to coact with the part of said bridge-piece in said recess to prevent longitudinal movement of said bolster, said lugs or ribs and bridge-piece forming the sole 95 means for that side of the car-truck to prevent lengthwise shifting of said bolster, substantially as described.

5. The combination of a car-truck side frame having a recess in its top surface, and 100 one or more angle-transoms fastened to said side frame, each transom having one flange resting on the top surface of the side frame and the other flange extending downwardly into said recess, substantially as described. 105

6. The combination of a car-truck side frame having a recess in its top surface adapted to accommodate the end of a bolster, a pair of angle-transoms fastened to said side frame, each transom having one flange resting on the top surface of said side frame and the other flange depending into said recess, and a bridge-piece extending over said recess and fastened to the two portions of said side frame on opposite sides of said recess, 110 115 substantially as described.

As evidence that I claim the foregoing as my invention I have signed the same, this 20th day of September, 1906, in the presence of two witnesses.

GEORGE G. FLOYD.
